(57) **CLAIM**

We claim the ornamental design for a dual handled exercise assembly, as shown and described.

DESCRIPTION

FIG. 1 is a perspective view of the assembled new dual handled exercise assembly design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawing views represent unclaimed portions of a dual handled exercise assembly, which are included for the purpose of illustrating unclaimed environment only, and form no part of the claimed design.
